UNITED STATES PATENT OFFICE.

CYRUS E. SWIHART, OF HARPSTER, OHIO.

DESIGN FOR A COMBINATION-TOOL.

57,394.

Specification for Design.

Patented Mar. 15, 1921.

Application filed May 29, 1919. Serial No. 300,743. Term of patent 7 years.

To all whom it may concern:

Be it known that I, CYRUS E. SWIHART, a citizen of the United States, residing at Harpster, in the county of Wyandot and State of Ohio, have invented a new, original, and ornamental Design for a Combination-Tool, of which the following is a specification, reference being had to the accompanying drawing, forming a part thereof.

The figure is a perspective view of a tool, showing my new design.

I claim:

The ornamental design for a combination tool, as shown.

CYRUS E. SWIHART.
